DESIGN FOR A DRESS

Mary Mullen, Philadelphia, Pa., assignor to Rose-nau Bros. Inc., Philadelphia, Pa., a corporation of Pennsylvania

Application September 11, 1936, Serial No. 64,808

Term of patent 3½ years

To all whom it may concern:

Be it known that I, Mary Mullen, a citizen of the United States, residing at Philadelphia, in the county of Philadelphia and State of Pennsylvania, have invented a new, original, and ornamental Design for a Dress, of which the following is a specification, reference being had to the accompanying drawing, forming part thereof:

I claim:

The ornamental design for a dress, as shown and described.

MARY MULLEN.
